UNITED STATES PATENT OFFICE.

CHARLES H. DUTCHER, OF JERSEY CITY, NEW JERSEY, ASSIGNOR TO KIELEY & MUELLER, INC., OF NEW YORK, N. Y., A CORPORATION OF NEW YORK.

DAMPER REGULATOR.

Application filed July 17, 1926. Serial No. 123,243.

This invention relates to automatic damper regulators and has particular reference to an improvement in hydraulic regulators especially designed for automatically controlling the dampers of boiler flues of low pressure systems whereby the dampers are opened or closed when the boiler pressure drops below or exceeds a predetermined pressure.

One of the principal objects of the present invention is to provide a hydraulic regulator which gradually opens or closes the damper relative to the pressure in the boiler so as to eliminate the common practice of instantly moving the damper from a fully closed to a fully open position, or vice versa.

Another object of the invention resides in the provision of an improved controlling valve for introducing the hydraulic pressure to the piston cylinder and cutting off and relieving said pressure through a single port and in making the valve bushing and plunger readily removable and renewable at a minimum expense and without undue loss of time.

Another feature of the invention is embodied in the provision of a counterbalancing device for the pressure-operated scale beam which permits the regulator to operate on extremely low pressures, such as vapor systems.

The invention furthermore comprehends a damper regulator which is comparatively simple in its general construction, inexpensive to manufacture and install, and which is thoroughly reliable and highly efficient in its purpose.

With the above recited and other objects in view, reference is had to the following specification and accompanying drawings in which there is exhibited one example or embodiment of the invention which is in no way intended as a limitation upon the scope of the appended claim as it is to be clearly understood that variations and modifications which properly fall within the scope of said claim may be resorted to when found expedient.

In the drawings—

Figure 1 is a vertical sectional view through the regulator;

Fig. 2 is a diagrammatic view illustrating its application to a damper;

Fig. 3 is an enlarged fragmentary sectional view of the valve illustrating the same in opened condition for admitting the hydraulic pressure to the hydraulic regulator piston cylinder;

Fig. 4 is a fragmentary sectional plan view taken approximately on the line 4—4 of Fig. 3;

Referring to the drawings of characters of reference, 10 designates a supporting bracket upon which a pressure chamber 11 is mounted, having a movable diaphragm 12, flexed by the boiler pressure which is led to the chamber through a pipe or conduit 13. The bracket also supports a hollow base 14, within which the inner end of a scale beam 15 is fulcrumed at 16. The diaphragm 12 on its upper outer face is provided with means 17 engaging under the scale beam for lifting or lowering the outer free end 18 of the same as the boiler pressure respectively increases or decreases. The outer free end of the scale beam 15 is adapted to support a weight or weights 19 in accordance with the pressure which it is desired to carry in the boiler. Supported upon and extending upwardly from the base 14, is a cylinder 20 having a spaced concentric inner sleeve 21 and defining between the cylinder and said sleeve a water-receiving chamber 22. The upper end of the cylinder 20 is closed by a head 23 and the upper end of the inner sleeve 21 is open and spaced below the head 23 to allow for communication between the water chamber 22 and the interior of the cylinder. A hydraulic regulator piston 24 is mounted within the cylinder for vertical movement and the piston rod 25 thereof extends upwardly through a stuffing box 26 in the head 23. The upper end of the piston rod 25 is provided with an eye 27 connected by a chain or other flexible element 28 with the arm 29 of the damper 30 pivoted in the boiler flue 31. The arm 29 supports at its free end a suitable weight or weights 32 and the flexible element is trained over guide elements 33. A hydraulic valve including a casing 34 is supported by a tubular stem 35 from the outer cylinder 20 and its bore or port 36 commun-

cates with the water chamber 22 and the interior of the valve casing 34. The valve casing is provided with a closed lower end 37, a lower bore 38 of less diameter than 5 an intermediate bore 39, which intermediate bore is of less diameter than the upper bore 40. A tubular bushing 41 having a reduced lower diameter 42, a relatively larger intermediate diameter 43, and a major upper diameter 44, is positioned in the valve casing and is provided with a tapered threaded portion 45 engaging a complementary tapered threaded portion 46 in the valve casing. The lower reduced diameter 42 is less than 10 the diameter of the lower bore 38, the intermediate diameter 43 of the bushing is less than the diameter of the intermediate bore 39, and the major diameter 44 of the bushing is less than the diameter of the upper bore 15 40 of the casing. The bushing is provided with an axial bore 47 and extending radially outward therefrom and through the respective diameters 42, 43 and 44 are ports 48, 49 and 50. A plunger valve 51 is axially movable in the axial bore 47 of the bushing and the same is provided with a central portion 52 of less diameter than the bore 47 and end portions 53 and 54 of approximately the same diameter as the bore 47, the 20 portions 53 and 54 being spaced apart a distance less than the axial spacing of the radial ports 48 and 50 so that when the ports 50 are opened, the ports 48 are closed, and vice versa, upon axial shifting movement of 25 the plunger valves. The upper end of the plunger valve is detachably connected by a coupling 55, with an actuator rod 56, which extends through a stuffing box 57 in the valve casing cap 58. A hydraulic pressure 30 conduit or pipe 59 leads into the upper compartment or bore 40 of the valve casing and an outlet conduit or pipe 60 leads from the lower compartment or bore 48 of said valve casing. The lever 61 is pivotally connected 35 at 62 to the upper end plunger valve actuator rod 56, and one extremity of said lever is pivotally connected at 63 to a connecting rod 64 which is in turn pivotally connected at 65 to the scale beam 15. The opposite extremity of the lever 61 is pivotally connected at 66 to a connecting bar 67, which connecting bar in turn is pivotally connected at 68 to the arm 69 of compensating lever 70. The compensating lever is 40 fulcrumed at 71 on a bracket 72 carried by the stem 35. The fulcrum 71 is eccentric to the pivotal connection 68 between the arm 69 and connecting bar 67. The compensating lever at its free end, is connected by a chain 45 or flexible connecting element 73 to a collar 74 secured on the piston rod 25. In order to counterbalance the weight of the scale beam 15, especially where the device is to be used on low pressure or vapor systems, a counter-

balancing weight 75 is fulcrumed at 76 to 65 a bracket arm 77 and is provided with an oppositely extending arm 78 connected by a connecting rod 79 to the scale beam.

In operation, assuming that the pressure in the boiler is below the predetermined 70 pressure which is desired, the regulator or piston 24 will be disposed at the upper end of its stroke or approximately in the position illustrated in Figs. 1 and 2, the damper 30 in the flue being fully opened as shown. 75 When the pressure in the boiler reaches the point which overcomes the weight of the scale beam, the pressure upon the diaphragm creates an upward force to move the scale beam up. The movement of the scale beam up opens the hydraulic valve by shifting the plunger 51 upwardly to substantially the position illustrated in Fig. 3, at which point the hydraulic pressure is admitted through the ports 50 between the valve heads 53 and 54, thence through the ports 49 to the bore or port 36 of the stem 35. The hydraulic pressure flows through the stem filling up around the sleeve 21 and thence to the upper side of the hydraulic piston 24 to cause the same to start on its downward stroke. As the piston moves down the compensating lever 70, which is weighted at 80 adjacent its outer end, gravitates downwardly as a slack 90 is produced in the chain or flexible element 95 73. The downward movement of the compensating lever causes the arm 69 thereof to move downwardly and exert, through the connecting bar 67, a downward movement on the lever 61 sufficient to move the valve 100 plunger 51 downwardly to cut off the hydraulic pressure without opening the port 48 to the outlet pipe. The valve remains in this position until slightly more pressure is exerted on the diaphragm for causing the 105 valve to open by the scale beam action. These operations are continued in succession until the regulation of the pressure has reached a definite predetermined point. In opening the damper, the action is reversed. 110

What is claimed is:

An automatic draft regulator for steam boilers, including a weighted beam arm, a diaphragm operable by the steam pressure in the boiler for moving the beam arm, a piston cylinder, a piston mounted in the cylinder having operative connection with the damper of the boiler flue, a hydraulic pressure valve connected with the cylinder, said valve having a hydraulic pressure intake 115 and exhaust and a shiftable valve plunger in said intake movable to position for respectively admitting hydraulic pressure to and exhausting said pressure from the cylinder at one side of the piston and for closing both the intake and exhaust to render the valve inactive, an actuating lever connected with the valve plunger for shifting 120 125

the same, a connection between one end of the actuating lever and the beam arm for shifting the valve to admit hydraulic pressure to and exhaust said pressure from the cylinder, and a connection between the opposite end of said lever and the piston for rendering the valve inactive, the said hy-

draulic pressure valve having a lower portion of reduced diameter provided with an internal thread, a valve plunger bushing ¹⁰ having a complementary external thread to facilitate the removal and renewal of the same when worn.

CHARLES H. DUTCHER.
